UNITED STATES PATENT OFFICE.

BURTON S. AIKMAN, OF MILWAUKEE, WISCONSIN, ASSIGNOR TO NATIONAL BRAKE & ELECTRIC COMPANY, OF MILWAUKEE, WISCONSIN, A CORPORATION OF WISCONSIN.

COMPRESSOR.

Application filed April 14, 1927. Serial No. 183,652.

My invention relates to pumps and more particularly to pneumatic pumps such as compressors, suction pumps and the like.

The present invention is more particularly concerned with the valve mechanism and discharge connections suitable for use on gas compressors.

In the development of a compressor suitable for operation at speeds above what is now standard in the art I have taken up the sleeve valve first proposed by Renault and developed the same to a point where I have been able to run the compressor at full motor speed with air cooling only. See my co-pending application Serial No. 180,433, filed April 2, 1927. In the construction therein described, I have employed a pneumatically operated seat member for holding a seal upon the intake valve sleeve. The discharge valve in that device is in a separate discharge valve chamber and is subjected on its top side to the heat of the compressed gases and on its bottom side it lies over the discharged valve port which therein constitutes a substantially dead space.

In accordance with the present invention I extend the aforesaid valve seat which structurally is a thin annular plate, radially inward and cause it to overhang a valve seat which forms a seal against the escape of compressed air back into the cylinder. This annular plate which forms the seat for the intake valve sleeve thereby forms the discharge check valve. The pressure which the intake valve sleeve exerts upon said annular plate assists the pneumatic pressure in opening the discharge check valve.

Upon recessional motion of the piston the discharge check valve promptly closes and the intake valve cannot open until the discharge check valve has closed. The intake passageway conducts the air taken into the cylinder directly in contact with said annular plate cooling the same.

In order to prevent the cumulative rise of temperature in the pocket above the discharge check valve, I have reduced the volumetric size of the pocket and the passageways communicating therewith to a minimum and insulated the same from thermal contact with the cylinder walls so that even if heating of a part of the structure does occur it cannot injure either the valve struc-

ture or seriously affect the piston and cylinder lubrication.

The valve of my invention is adapted to be used with the sleeve valve actuated either by ring friction or by mechanical means.

The actuation of the valve sleeve partly by ring friction and partly by pneumatic pressure constitutes the preferred construction since in that form there is a nice balance between the pneumatic forces operating to hold the sleeve valve closed and to hold the discharge check valve closed.

While it would be possible to have a ring type intake valve contacting normally with the discharge valve and to permit the pneumatic difference in pressure on the suction stroke to open the same it is to be observed that such construction is not as effective as the construction employing the sleeve valve where said sleeve valve has a definite traverse to and from its seat since the sleeve valve having such definite traverse is self-cleaning.

Now in order to acquaint those skilled in the art with the manner of constructing and operating a device embodying my invention I shall describe in connection with the accompanying drawing a specific embodiment of the same.

Fig. 1 is a longitudinal vertical section through the upper end of the cylinder and head, showing the valve mechanism of the compressor in the position it occupies during the intake stroke of the piston;

Fig. 2 is a like section showing the valve mechanism in the position it occupies during the discharge stroke;

Fig. 3 is a fragmentary sectional view of a modified form in which the sleeve valve is operated by a cam;

Fig. 4 is a fragmentary sectional view showing a modified form of the valve seat for the intake and discharge valves.

Referring now to the structure shown in Figures 1 and 2, the compressor comprises a cylinder 1, having a head 2, these parts being joined by suitable clamping flanges 3 and 4 respectively. The upper end of the cylinder 1 comprises an annular air chest or trunk 5, communicating with intake passageway 6. Air is preferably forced into said trunk under pressure in accordance with my prior Patent 1,611,866 for scavenging and super-charging the cylinder. The head

2 is provided with radiating fins and the cylinder may likewise be so provided. The head 2, has an opening 7 therethrough, this opening extending through a hollow boss 8 which comprises substantially no more than a cylindrical flange extending from the top of the head, this opening being closed at the lower end by a plug 10 which seats on the annular shoulder 9 to form a tight closure 10 for said opening 7. The plug 10 has a hollow stem 11 extending up through the hollow boss 8 and this hollow stem is threaded at 12 to receive the lower threaded portion of the coupling 13 which coupling has a flange 14 resting on the upper edge of the cylindrical hollow boss 8. The coupling 13 furthermore has a threaded socket at 15 for receiving the lower end of the discharge pipe 16 which surrounds the upper end of the hollow stem 11. By drawing the coupling 14 tight on the thread 12 the plug 10 which seats against the annular shoulder 9 is drawn tight to form a seal. A dead pocket 17 is thereby formed in the hollow boss 8 to serve as an insulating medium.

The plug 10 has a plurality of radial passageways 18, 18 extending from the periphery thereof to the central portion where these passageways communicate with the 30 passageway 19 in the hollow stem 11. The hollow stem 11 extends up above the connection between the coupling 14 and said stem which connection occurs at the threaded portion 12 so that the upper end of said hollow 30 stem is insulated thermally from both the discharge pipe 15 and from the coupling 13.

The plug 10 has at its lower peripheral edge an overhanging radial flange 20 which provides a flat valve seat for engagement 40 by the inner margin of a thin annular plate valve the outer margin of which is clamped between a seat 22 and the edge 23 of a clamping ring 24. The seat 22 to which the outer margin of the plate 21 is clamped projects 45 downward below the bottom space of the head 2 so as to provide a clearance at 25 for the inner free edge of said valve. This forms in connection with the annular clearance or passageway 26 the valve chamber for 50 said plate valve 21 and the valve chamber communicates through the radially extending port 18 with the common discharge passageway 19 and the hollow stem 11.

The cylinder 1 is provided with a movable 55 sleeve 27 within which is fitted the working piston 28 said piston being reciprocated by the usual crank shaft in the well known manner. The sleeve 27 constitutes a valve controlling the intake and assisting in controlling the discharge of gas to and from the interior of the same. This valve sleeve has a light traverse to and from the check valve 21. At its upper end it is provided with an inwardly extending flange 29, having a relatively narrow seat 30 at its

upper edge adapted to engage the bottom surface of the plate or ring valve 21, between the seat 20 and the clamping seat 22. The valve sleeve 27 is provided with a flange 31 which is adapted to engage a yielding 70 stop 32 which may be of fibrous composition placed in a groove or seat above the inwardly projecting flange 33 in the wall of the cylinder 1. The flange 33 fits loosely the outer surface of the valve sleeve 27. The 75 upper end of the sleeve 27 is guided in wing guides 34 depending from the ring 24. A suitable stationary guide at the bottom end of the sleeve is provided although this is not shown in the drawing.

The operation of the device shown in Figures 1 and 2 is as follows: Assume that the piston 28 is moving downwardly on the suction stroke as shown in Fig. 1. As soon as the piston starts down the ring friction moves the sleeve 27 so that the collar or flange 31 engages the yielding stop 32 moving the valve sleeve 27 downwardly a definite distance to open a passageway over the top of the flange 29 and the bearing face 30. 80 Air enters between the flange 29 and the ring 24, passes in contact with the ring valve 21 between the stationary seat member 20 and engages the flange or seat 20 near the upper end of the valve sleeve and passes 85 down into the interior of the cylinder. It will be observed that the incoming gas thereby contacts directly with the discharge check valve and with the flange 20 which forms the seat for said discharge check valve thereby 90 cooling the same. Where the blower described in my previously mentioned patent is used in connection with a device of this kind the heat which is conveyed to the first part of the incoming gases is largely dissipated by the excess flow of air created by said blower and the consequent cooling and scavenging which results. The air which is blown into the wind chest 5 in excess of the 95 requirements of the compressor cylinder is 100 discharged against the top of the head for cooling purposes.

When the piston 28 has reached the bottom of its stroke the cylinder is full of air at atmospheric pressure or slightly above the same. The piston 28 then begins to rise and its initial upward motion moves the valve sleeve 27 upward to the point where the engaging face 30 of the turned flange 29 contacts with the ring check valve 21, said check valve remaining closed until such time as the internal pressure in the cylinder is great enough to lift the check valve 21 into the position shown in Figure 2 whereupon the discharge of compressed gases from the cylinder into the annular pocket and passageway 26 occurs. From this annular passageway 26 the gases pass through the radial passageway 18 into the central passageway 19 in the hollow stem 11 and from thence 110

are discharged on up into the discharge pipe 16.

There is a nice pneumatic balance which controls the operation of the discharge check valve. The ring friction is not sufficient to lift the valve where any appreciable pneumatic pressure exists above the check valve but this ring friction is sufficient to apply the sleeve to its seat against the annular 10 plate 21 which forms the discharge check valve. As soon as compression within said cylinder has risen to the point where the pressure in the cylinder is substantially equal to or slightly greater than the pressure 15 sure above the discharge check valve this check valve will be in substantial balance pneumatically, the only force at that time being the ring friction tending to raise the sleeve 27 and the spring of the plate 21 tending to hold it to its seat.

The internal diameter of the cylinder and the external diameter of the clearance 25 are made substantially equal so that the pneumatic pressure tending to force the valve 21 downward is substantially equal to the pneumatic pressure tending to force the valve sleeve upward. If desired a slight preponderance of upward pressure may be provided to assist in lifting the valve 21 from its seat. 20 I preferably make the areas of the same diameter so that a slightly higher pressure must prevail in the cylinder before the valve 21 is lifted from its seat corresponding to present practice where a discharge check 25 valve is loaded with a spring to compel a slightly higher pressure in the cylinder to be generated before the discharge check valve opens.

The lift of the valve 21 may be made very 20 slight and yet ample discharge opening is provided because of the large diameter of the same with respect to the size of the cylinder.

Since this valve 21 has such a large effective diameter it is desirable to reduce the contact of the gases therewith to a minimum to secure the best results. It is undesirable to have a large mass of hot gases remaining in contact with the valve or with the head 50 and for this reason I make the annular passageway 26 and the clearance 25 above the valve 21 as small as practicable. At the same time I restrict the passageway 18 and the central passageway 19 to reduce the volumetric content of hot compressed gas and to compel relatively rapid discharge of the gases therethrough. At the same time it will be observed that the plug 10 has contact with the head 2 so far as the direct transmission of heat is concerned only through the narrow seat 9. The central hollow stem 11 is not connected directly to the head and any transmission of heat from said hollow stem 11 to the head can occur only through 55 a relatively long pathway which is exposed

to external cooling, this long path of travel of the heat comprising the coupling 13 and the hollow boss 8. The upper end of the hollow stem 11 is surrounded by a dead air space so that the transmission of heat to or from said hollow stem 11 is retarded to as great an extent as is possible. Any heat passing from the discharge pipe 16 back to the head must follow a relatively long path also exposed to external cooling.

This valve arrangement permits of a reduction of the clearance space to a minimum without projections on the piston.

I believe that the form of discharge check valve here shown is novel broadly and I am aware that it is not essential that the valve sleeve 27 be sealed directly against the discharge valve 21. For example, a separate seat in the form of an annular plate 35 may be provided as shown in Figure 4 for sealing the upper end of the valve sleeve 27 said plate having its free inner edge engaged by the upper edge 30 of said valve sleeve 27. In this form the incoming air cools both the seat 35 and the discharge check valve 21.

Also it is to be understood that it is not essential that the valve sleeve be operated solely by ring friction.

In the modification diagrammatically illustrated in Figure 3 the intake valve sleeve 36 has the straight cylindrical upper end guided in the guide 38 which extends from the clamping ring 24 corresponding to the guiding finger 34 mounted on the clamping ring 24 shown in Figures 1 and 2. The upper end of the sleeve 36 is brought into engagement with the annular plate valve 37, the inner margin of which seats on the seat 20 and the outer margin of which is clamped under the edge 23 of the clamping ring 24. The valve sleeve 36 is actuated by a rocking lever 40 pivoted on a stationary pivot at 41 and pivotally connected at 42 to said sleeve 36. At its outer end the lever 40 is connected by the pin connection 43 with a thrust rod 44 which in turn is pivoted at 45 to the lower rocking lever 46. This lower rocking lever 46 is pivoted at 45 to the thrust rod 44. This lower rocking lever 46 has a stationary pivot at 47 and has a cam follower 48 in the shape of a roller engaging the cam 49 on the crank shaft 50. The follower 48 is held in contact with the cam 49 by a compression spring 51 which bears against a stationary web 52 through which the stem or rod 44 passes. This form of intake valve and cam operating mechanism is disclosed in my co-pending application Serial No. 185,713, filed July 28, 1927, to which reference is here made for a detailed description and illustration of the same.

In the present construction the plate 37 has sufficient yield that when the valve sleeve 36 is raised in contact with the same the inner margin will not leave the seat 22

until the pressure within the cylinder on the compression stroke rises to the discharge pressure above said valve plate 37 whereupon the free margin leaves seat 22 and opens communication between the interior of the cylinder and the discharge passageway 26. In this construction it is preferable to make the annular valve plate 37 of greater radial extent than is required in the forms shown in Figures 1 and 2.

It is furthermore apparent that the valve sleeve 36 may engage a separate seat such as the yielding plate 23 shown in Figure 4. In other words a separate seat may be provided for the intake valve sleeve without departing from the broad aspect of the invention.

One great advantage of the present invention is the ability to open the discharge check valve without any appreciable preponderance of pressure in the cylinder. This means faster delivery of the compressed gas, greater volumetric efficiency and better overall efficiency.

In practice the ring friction and counter pressure due to the spring of the valve 21 substantially balance each other with the result that very little excess pressure opens the valve. If desired the ring friction may be greater than the counter spring pressure of the valve.

I do not intend to be limited to the details shown and described.

I claim:

1. In a device of the class described, a cylinder having a head therefor, a valve sleeve in said cylinder, a piston in said sleeve, an annular plate secured at its outer margin to said head, a circular plate secured to said head, said plate having a flange extending radially outward beyond the inner edge of the annular plate to form a valve seat engaged by the inner margin of said annular plate, said valve sleeve being adapted to engage the annular plate and form a pneumatic seal in conjunction therewith.

2. In a compressor, the combination of a cylinder having a head, said head having an aperture, a plug closing said aperture, said plug having a radially extending flange at its lower edge, an annular plate loosely embracing said plug and having a free inner margin spaced from the head and contacting with the flange to form a valve, the outer margin of said annular plate being clamped to said head, there being a chamber formed about the periphery of the plug above the said flange, said plug having a central discharge passageway and passageways communicating between said central discharge passageway and the chamber.

3. In a compressor, a head member having a central opening therethrough, said head having a cylindrical flange about said opening, a circular shoulder about said opening, a plug member seated against said shoulder,

and forming a closure for the opening, said plug having a radially extending flange at its periphery and having a hollow stem, there being passageways from the periphery of the plug above said radial flange to said hollow stem, a thin annular plate valve seating upon said radial flange and a threaded coupling member connected to said hollow stem, and bearing against said cylindrical flange to keep the plug member seated against the shoulder.

4. In a compressor, a head member having a central opening therethrough, said head having a cylindrical flange about said opening, a circular shoulder about said opening, a plug member seated against said shoulder, and forming a closure for the opening, said plug having a radially extending flange at its periphery and having a hollow stem, there being passageways from the periphery of the plug above said radial flange to said hollow stem, a thin annular plate valve seating upon said radial flange, a threaded coupling member connected to said hollow stem and bearing against said cylindrical flange to keep the plug member seated against the shoulder, said coupling member having a threaded socket and a discharge pipe loosely embracing said hollow stem and threaded into said latter socket.

5. In a compressor, the combination of a cylinder, a head therefor, said head having an annular discharge passageway, a discharge check valve for said passageway, said valve comprising a thin annular plate closing said annular passageway, and an intake valve sleeve in said cylinder, a piston in said sleeve, said valve sleeve when in open position permitting the air drawn into the same by the piston to sweep past and cool the said discharge valve.

6. In a compressor, a cylinder having a head, said head having an annular discharge passageway, an annular plate valve for said passageway, a piston and a cylindrical intake valve sleeve, said sleeve engaging said annular plate valve upon the discharge stroke of the piston and tending to lift the same from its seat.

7. In a compressor, the combination of a cylinder having a head, said head having an annular discharge passageway, an annular plate valve for said passageway, said cylinder having an annular intake pocket, a cylindrical valve sleeve having a traverse toward and away from said annular plate valve, said sleeve having a piston therein and being adapted to be opened upon the suction stroke of the piston, said valve when open permitting the piston to draw air from said annular intake pocket past said annular discharge valve to cool the same.

8. In a compressor, a cylinder having a head, said head having an annular discharge passageway, an annular valve seat, an annu-

- lar plate valve sealed to the head about its outer periphery and seating on said annular valve seat to control said discharge passageway, an intake valve sleeve and a piston 5 therein, said sleeve upon the beginning of the discharge stroke of the piston being forced into contact with said plate valve and tending to lift it from its seat.
9. In a compressor, a cylinder, a head therefor, a piston for the cylinder, said head having a discharge port, a discharge valve controlling the port, an inlet valve sleeve and means for pressing the sleeve against the discharge valve during the compression 10 stroke of the piston.
10. In a compressor, the combination of a cylinder, a head having an annular discharge passageway and providing an annular valve seat at the inner periphery of the same, a thin 15 annular plate valve closing said passageway, the outer edge of said valve being rigidly clamped to the head, the inner edge being free to move to and from said seat and an intake valve sleeve having a seat disposed 20 radially outside the aforesaid seat, said cylinder and head having an intake passageway, one wall of which is defined by said plate valve.
11. In a compressor, the combination of 25 a cylinder, a head therefor, said compressor having an intake passageway and a discharge passageway, an intake valve, a piston for said cylinder, said intake valve being movable to open and close the intake passageway, a discharge valve, said intake valve seating against said discharge valve at the 30 beginning of the compression stroke to close the intake passageway and said discharge valve being unseated by pneumatic pressure 35 after it is engaged by said intake valve.
12. In a compressor, a cylinder, a head therefor, a piston for the cylinder, said compressor having an intake passageway and a discharge passageway adapted to communicate with the interior of the cylinder, 40 said discharge passageway having an annular valve seat, an annular plate valve clamped to said head about its outer margin and seating upon said seat at its inner margin, and an intake valve sleeve in the cylinder 45 controlling the intake passageway and seating when closed against said discharge check valve.
13. In a compressor, the combination of 50 a frame, a head secured thereto, an intake valve sleeve cooperating with the head to form a working cylinder, a piston in said cylinder, said compressor having an intake passageway controlled by said sleeve, a discharge passageway, a thin annular plate valve controlling said discharge passageway and forming when closed one wall of the intake passageway.
14. In a compressor, the combination of a 55 frame, a head secured thereto, an intake valve sleeve cooperating with the head to form a working cylinder, a piston in said cylinder, said compressor having an intake passageway controlled by said sleeve, a discharge passageway, a thin annular plate valve controlling said discharge passageway and forming when closed one wall of the discharge passageway.
15. In a compressor, the combination of a frame, a head secured thereto, an intake valve sleeve cooperating with the head to form a working cylinder, a piston in said cylinder, said compressor having an intake passageway controlled by said sleeve, a discharge passageway, a thin annular plate valve controlling said discharge passageway and forming when closed one wall of the intake passageway, said valve sleeve when closed defining one wall of the discharge passageway.
16. In combination, a frame, a head member secured to the frame, an intake valve sleeve slidably mounted in the frame and cooperating with the head to define a working chamber, an annular intake valve passageway surrounding the upper end of said sleeve, an annular clamping seat on the bottom of the head, an annular valve seat depending from said head, a thin annular plate valve secured to the clamping seat and cooperating with the other seat to form a discharge check valve, said intake valve sleeve being adapted to engage said thin annular plate between the clamping seat and the depending seat.
17. In combination, a cylinder frame, a head secured thereto, a valve sleeve mounted in the frame, a central opening through the head, a tubular extension on the head surrounding said opening, an annular shoulder about the lower end of the opening, a plug member seating against said shoulder, said plug member having a hollow stem, a coupling member resting on the upper end of said tubular extension and engaging the hollow stem, said coupling having a threaded pipe socket for receiving a discharge pipe.
18. In combination, a cylinder head having an opening therethrough, a tubular extension on the head surrounding the opening, a circular plug closing the lower end of the opening, said plug having a hollow stem extending out through the tubular extension, a coupling having a flange overhanging the edge of the tubular extension and having a body displaced axially from said flange and secured to the hollow stem, said coupling having a pipe socket for connecting a discharge pipe.
19. In combination, a cylinder head having an opening therethrough, a tubular extension on the head surrounding the opening, a circular plug closing the lower end of the opening, said plug having a hollow stem extending out through the tubular extension,

- 6
- a coupling having a flange overhanging the edge of the tubular extension and having a body displaced axially from said flange and secured to the hollow stem, said coupling 5 having a pipe socket for connecting a discharge pipe, said plug having a radially extending flange below the surface of the head and an annular plate valve cooperating with said flange to form a discharge check valve.
- 10 20. In a compressor, having a head provided with a discharge passageway, a cylinder provided with an intake passageway and an intake sleeve valve there being an annular passageway between the sleeve and the head, 15 the lower end of said passageway communicating with the interior of the sleeve valve, the upper end of the annular passageway being adapted to communicate alternately with the intake passageway and the discharge passageway, the sleeve valve controlling said communication with the intake passageway and a check valve controlling said communication with the discharge passageway. 20
21. In combination, a cylinder head having an annular seat, a ring valve of thin metal having its outer peripheral margin disposed on said seat, a clamping ring for clamping said outer margin on said seat, said head providing a clearance under the inner peripheral margin of said ring valve, and 25 means providing an external seat for the free margin of said valve.
- In witness whereof, I hereunto subscribe my name this 9th day of April, 1927.
- BURTON S. AIKMAN.
